(57) CLAIM

The ornamental design for a golf cart canopy and related storage housing, as shown and described.

DESCRIPTION

FIG. 1 is a perspective view of my new design with the canopy in the deployed position, and the golf cart roof shown in dashed lines;

FIG. 2 is another perspective view of my new design with the canopy in the deployed position;

FIG. 3 is a side view of my new design with the canopy in the deployed position;

FIG. 4 is a rear view of my new design with the canopy in the deployed position;

FIG. 5 is a top view of my new design with the canopy in the deployed position;

FIG. 6 is a side view of my new design with the canopy stored in the housing;

FIG. 7 is a rear view of my new design with the canopy stored in the housing; and,

FIG. 8 is a perspective view of a second embodiment of the golf cart canopy and related storage housing, the only difference being the number of bars supporting the canopy. The broken line showing of environment is for illustrative purposes only and forms no part of the claimed design.

The golf cart canopy is shown on an enlarged scale in FIGS. 2–7.
